UNITED STATES PATENT OFFICE.

EFFIE R. REDMAN, OF CHICAGO, ILLINOIS, ASSIGNOR TO SUPREME GUARDIAN COUNCIL OF THE ORDER OF JOB'S DAUGHTERS, OF OMAHA, NEBRASKA.

DESIGN FOR AN EMBLEM OR SIMILAR ARTICLE.

Application filed January 4, 1927. Serial No. 20,277. Term of patent 14 years.

To all whom it may concern:

Be it known that I, EFFIE R. REDMAN, a citizen of the United States, residing in Chicago, in the county of Cook, State of Illinois, have invented a new, original, and ornamental Design for an Emblem or Similar Article, of which the following is a specification, reference being had to the accompanying drawing, forming part thereof.

In the accompanying drawings Figure 1 is a plan view of the emblem or similar article showing my new design.

I claim:

The ornamental design for an emblem or similar article, substantially as shown.

EFFIE R. REDMAN
